UNITED STATES PATENT OFFICE.

HARRY H. HISTAND, OF DOYLESTOWN, PENNSYLVANIA.

SNOW-GUARD.

No. 907,355.

Specification of Letters Patent.

Patented Dec. 22, 1908.

Application filed November 22, 1907. Serial No. 403,371.

To all whom it may concern:

Be it known that I, HARRY H. HISTAND, citizen of the United States, residing at Doylestown, in the county of Bucks and State of Pennsylvania, have invented certain new and useful Improvements in Snow-Guards, of which the following is a specification.

The object of this invention is an improved snow guard which is adapted to be attached to a slate or shingle roof or the like and which is designed to prevent the snow from sliding off of the roof after thawing loose.

With this and other objects in view as will more fully appear as the description proceeds, the invention consists in certain constructions and arrangements of parts that I shall hereinafter describe and claim.

For a full understanding of the invention and the merits thereof, reference is to be had to the following description and accompanying drawings, in which:

Figure 1 is a perspective view of my improved snow guard. Fig. 2 is a front elevation thereof showing it applied. Fig. 3 is a side elevation thereof showing it in position upon a roof. Fig. 4 is a plan view.

Corresponding and like parts are referred to in the following description and indicated in all the views of the drawing by the same reference characters.

My improved snow guard is preferably constructed of an integral strip of wire or the like, comprising a main portion or shank 1, the rear end 2 of which is angularly disposed, extending downwardly therefrom and tapering to a point. The other or front end of the main portion is bent to form an upwardly extending diamond-shaped abutment 3 the three upper corners of which are looped as shown at 4. The extremity is then bent to form a ring-like foot 5 which lies in a plane substantially perpendicular to the plane of the loops 4 and extends forwardly from the abutment 3, said loop being elevated by the thickness of the wire above the main portion 1.

In the application of my improved snow guard to a slate roof, the shank 1 thereof is fitted in the joint between two adjacent

slates of the same course with its front end extending upwardly from the margin portion of said slates and the rear end 2 extending downwardly through the cover portion thereof and being embedded in the sheathing of the roof to hold the device in place. When the next course of slates is added, the portion of the device positioned between the cover portions of the first-named course of slates will be hidden from view, thus leaving the front end of the device in the proper position upon the roof as shown.

The abutment 3 prevents the snow from sliding off of the roof after it has thawed loose, the loops 4 of said abutment serving to ornament it and also to stiffen it. The foot 5 rests on the adjacent portions of the two slates, as is permitted by its elevation above the main portion 1, and forms a relatively large bearing surface which serves as a brace for the abutment to assist the latter in withstanding the strain exerted thereon by the weight of the melting snow.

It is to be understood that this improved snow guard is described and shown as applied to a slate roof for the purpose of illustration only and that it is equally applicable to shingle roofs or the like.

Having thus described the invention, what I claim is:

The herein-described snow guard constructed of an integral strip comprising a shank, the rear end of which is bent downwardly and the forward end of which is oppositely disposed to form an abutment, the forward extremity of the strip being bent to form a loop lying in a plane perpendicular to the plane of the abutment and constituting a foot, said foot being raised above the shank and extending forwardly from the abutment, so as to form a bearing surface to brace the latter and coöperate with the rear end of the strip to secure the device firmly in position.

In testimony whereof I affix my signature in presence of two witnesses.

HARRY H. HISTAND. [L. s.]
